UNITED STATES PATENT OFFICE

147,939

DESIGN FOR A LAMP CASING OR SIMILAR ARTICLE

Philip O. Wright, Detroit, Mich., assignor to Packard Motor Car Company, Detroit, Mich., a corporation of Michigan

Application January 25, 1946, Serial No. 125,966

Term of patent 7 years

(Cl. D48—16)

To all whom it may concern:

Be it known that I, Philip O. Wright, a citizen of the United States, residing at Detroit, county of Wayne, State of Michigan, have invented a new, original, and ornamental Design for a Lamp Casing or Similar Article, of which the following is a specification, reference being had to the accompanying drawing, forming a part thereof.

Figure 1 of the drawing is a perspective view of a lamp casing incorporating my new design showing the same as it appears when in use on a vehicle body, the vehicle body being fragmentarily shown in dotted lines;

The characteristic features of my design reside in the portion shown by means of full lines in the drawing.

I claim:

The ornamental design for a lamp casing or similar article, substantially as shown and described.

PHILIP O. WRIGHT.
